UNITED STATES PATENT OFFICE.

MEADE WILDRICK, OF THE UNITED STATES ARMY, ASSIGNOR OF ONE-HALF TO
OSCAR I. STRAUB, OF THE UNITED STATES ARMY.

MOBILE MOUNT FOR HEAVY ARTILLERY.

1,371,962.

Specification of Letters Patent. Patented Mar. 15, 1921.

Application filed October 6, 1917, Serial No. 195,120. Renewed June 3, 1920. Serial No. 386,287.

To all whom it may concern:

Be it known that I, MEADE WILDRICK, of the United States Army, a citizen of the United States, stationed at Fort Monroe, in the county of Elizabeth City and State of Virginia, have invented certain new and useful Improvements in Mobile Mounts for Heavy Artillery; and I do hereby declare the following to be a full, clear, and exact description of the invention, such as will enable others skilled in the art to which it appertains to make and use the same.

My present invention relates to improvements in mobile mounts for heavy artillery. It is eminently desirable that heavy artillery should be readily transported from place to place and properly and readily mounted as emergency may require.

It has hitherto been the practice, whenever practicable, to prepare in advance solid foundations of concrete, or other suitable material, and then to transport the gun and its mount to this emplacement and secure it thereto, as with permanent fortifications. To prepare such emplacements requires undisturbed possession of the terrain for a sufficient length of time to have the foundations prepared and have the cement or concrete set; and when heavy artillery is advancing into the enemy's country the preparation of such emplacements is generally impracticable.

According to my present invention I provide a movable platform which may be transported by rail or auto cars from place to place, and which may be quickly mounted upon the ground, which may be quickly leveled therefor, and then I run the gun and its mount upon this portable platform which serves to all intents and purposes like the concrete emplacements well known in the art.

In order to accomplish these results, for large guns the gun platform is preferably carried separate from the gun, and the gun is moved forward upon the platform or withdrawn therefrom when desired. For small guns, the gun and racer may be both placed on platform car or carriage.

My invention will be more clearly understood after reference to the accompanying drawings in which:—

Figure 1 shows the gun mounted on railroad trucks, and the gun platform mounted on another pair of railroad trucks;

Fig. 2 shows the gun and its mount mounted on one set of auto trucks, and the gun platform mounted on another set of auto trucks;

Fig. 3 shows a side elevation of the platform in place with the gun run up thereon, but before the trucks have been removed, parts being shown as broken away;

Fig. 4 is a plan view showing the gun and mount in place, parts being broken away;

Fig. 5 shows a section along the broken line 5—5 of Figs. 3 and 4, and looking in the direction of the arrows;

Fig. 6 shows a section along the line 6—6 of Fig. 1, and looking in the direction of the arrows, parts being shown on a larger scale than in Fig. 1;

Fig. 7 shows the platform car with the racer traversing system as a part of it instead of as a part of the gun carriage car as shown in Fig. 1; and

Fig. 8 shows the gun mounted directly on the platform car or carriage for use with small guns, where the extra weight will not be excessive.

The gun 1, constituting a heavy piece of ordnance, is mounted on a carriage 2, which in turn is mounted on the platform 3 supported in position by the base ring 4, having the flange 5 bolted to the foundations provided in the emplacement, which will be hereinafter described.

In Fig. 1 the gun and its carriage are shown as temporarily supported on two trucks 7, traveling on the rails 10; while in Fig. 2 the gun and its mount are shown as supported on traction wheels 7^a, traveling on a roadbed 10^a. Except for the supporting means there is no difference between the constructions shown in the two figures.

The method of supporting the gun on the trucks and removing the trucks therefrom is fully described in my Patent 1,311,786, of July 29, 1919, and will not be described in detail herein.

The auxiliary platform on which the gun and the gun platform are rotatably mounted comprises a main frame 11 mounted on the trucks 12, as shown in Fig. 1, or upon the traction wheels 12^a, as shown in Fig. 2. Except for the mode of supporting this auxiliary platform when being transported from place to place, the structure is substantially the same in both Figs. 1 and 2.

The main frame 11 has a downwardly projecting central portion 11^a, and downwardly projecting lugs 11^b near its ends, and also downwardly projecting slotted members 13, provided with laterally projecting arms 13^a.

The arms 14 are hinged as at 14^a to these parts 11^a and 13, as shown in Fig. 3, and are secured to the heavy plates 15 provided with holding members or spades 16 on the ground face, when in the lowered position as shown in Figs. 3 and 5. These plates 15 are also provided with holes 17, through which holes the stakes 21 are driven when the auxiliary platform is in the operative position as shown in Fig. 5.

Hinged to the arms 13^a, carried by the main frame 11, are the locking arms 18 which are adapted to swing inward about their hinge pins 19, as shown in Figs. 1 and 3, or outward to the locking position for holding the plates 15 down, as shown in Figs. 4 and 5. The outer ends of these locking arms are preferably secured to the plates 15 when the latter are in the distended position, by means of the bolts 20, as shown in Fig. 5.

The plates 15 are raised when it is desired to move the auxiliary platform by means of the tackles 22, connected to the head of the derrick 23, which derrick consists of two members hinged together as at 23^a, and having their feet bolted as at 24 to the main frame 11. After the plates 15 are lowered to the position shown in Figs. 4 and 5, the tackles are disengaged from the eye-bolts 22^a; and the arms 23 are removed from the main frame so as to permit the moving of the gun and its mount upon the auxiliary platform and the training of the gun after it is mounted thereon.

When in transport the main frame 11, and the parts carried thereby, are supported at each end on the trucks as shown in Fig. 6, in which 30 represents L-shaped sliding blocks which engage the downwardly projecting members 11^b on the main frame. The inner ends of these blocks support the king bolt 32 when in the position shown in Fig. 6, but when it is desired to lower the main frame 11, with the parts carried thereby, as when the auxiliary platform arrives at the emplacement for the gun, the main frame 11 is lifted by means of the jacks 34 carried by the truck 12, as fully described in my Patent 1,311,786, of July 29, 1919 aforesaid. These blocks 30 may be then moved outward by means of the screws 31, in which event the lugs 11^b of the main frame freely project down between said blocks 30, as shown in Fig. 5.

Above the king bolt 32 is provided a plate 35 and a door 36, and by lifting the door and removing this plate the king bolt may be lifted out entirely if desired.

37, shown in Figs. 3 and 4, represents a ramp or inclined plane on which the gun mount may be run on to the auxiliary platform when the latter is in the operative position as shown in Figs. 3 and 4.

The upper part of the main frame 11 is provided with grooves 38 to guide the wheels of the trucks on which the gun platform is supported. After the auxiliary platform is all ready to receive the gun and its mount, the whole is run up the ramp, the wheels of the trucks engaging the grooves 38 until the bolt holes 40 in the flange 5 of the base ring register with the corresponding bolt holes 41, provided in the webs 42 of the main frame, and when the base ring is in the proper position the bolts 43 are inserted. For convenience in inserting these bolts, end sockets 44 are provided, as shown in Fig. 3.

The gun platform is connected to the base ring by means of the flange 50, and rotates upon the racer provided with anti-friction gun bearings 51. On its inner face the base ring is provided with a circular rack 52 adapted to engage the pinion 53, which is rotated by the wheel 54, which may be operated by hand, or in any other convenient way, as by a ratchet and pawl hand lever, such as is well known in the art.

By turning this pinion 53 the gun platform may be traversed, and the gun trained in azimuth, as may be desired.

The operation of the apparatus is as follows:

When in transit the gun and the auxiliary platform are mounted either on the railroad trucks shown in Fig. 1, or on auto trucks as shown in Fig. 2. They may be pulled as separate cars either by a locomotive or a tractor, or coupled together as a single train as desired.

When in transit, the gun platform carrying the base ring is supported clear of the roadbed, and the auxiliary platform has its wing plates 15 raised and its locking arms 18 swung in, as shown in Figs. 1, 2 and 6.

The surface of the ground at the point or emplacement it is desired to mount the platform is first leveled, as far as practicable, and then the auxiliary platform is run up to said emplacement. The wing plates 15 are then lowered into position and the locking arms 18 are swung out and bolted to the plates 15, as at 20, see Fig. 5. The derrick 23 and tackle 22 are removed. The main frame 11 is lifted slightly by means of jacks 34 so as to permit the supporting blocks 30 to be moved outward, by means of the hand worm gear 31. The platform frame 11 is now supported by the jacks 34, and is lowered by means of the jacks 34 until it rests upon the ground. The trucks 12 may be allowed to remain in position, or may be withdrawn as desired. The platform is now

secured to the ground by means of the stakes 21 and the emplacement is ready for the gun to be placed thereon.

The emplacement for the gun being ready, the ramp 37 is put in place, as indicated in Fig. 3, and the trucks bearing the gun and its mount are run or hauled up the ramp, and the base ring is located so that the bolt holes 40 and 41 will register as indicated in Fig. 3. Up to this time the gun platform 3 is supported on the trucks 7 or 7^a, as the case may be. Operate the jacks 6 causing their heads 6^a to project downward to engage the upper surface of the main frame 11, and by means of these jacks lift the gun platform 3, with the parts carried thereby, high enough to remove the trucks, which may be done in the manner described in my Patent 1,311,786, of July 29, 1919, aforesaid. Then ease up the pressure on the jacks, lower the base ring, with the parts supported thereby, to the main frame and secure it in place by inserting the bolts 43.

The gun is now ready to be loaded, trained in the desired direction and fired.

For the sake of clearness in the drawings I have omitted the elevating gear, such gear not constituting a part of my present invention, but it will be obvious that any suitable elevating gear may be used if desired.

When the gun is elevated as shown in dotted lines in Fig. 3, the breech projects down into the opening 3^a in the gun platform 3, and the gun is brought back to the substantially horizontal position for loading.

In order to remove the gun to another emplacement reverse the operation just described. It will be seen that a rigid and broad base is supplied for the gun mount, which may be readily supported on even soft ground, and the ground need not be leveled with any special degree of care.

It will be noted that the spades 16 and the stakes 21 will hold the auxiliary platform against being thrown out of place incident to the shock of discharge of the gun, and that substantially all the advantages of a concrete emplacement may be secured, and that the auxiliary platform may be in a very short time quickly removed to another emplacement.

It will be obvious that various modifications might be made in the herein described construction, and in the combination and arrangement of parts which could be used without departing from the spirit of my invention.

Having thus described my invention, what I claim and desire to secure by Letters Patent of the United States is:—

1. A mobile mount and emplacement for heavy artillery, comprising a base ring, a gun platform supported thereon, and a gun

carriage and gun mounted on said platform, trucks supporting the ends of said platform, means for raising said base ring and the parts supported thereon clear of said trucks, and a mobile auxiliary platform comprising a main frame and wing plates hinged thereto, with means for raising and lowering said wing plates and securing the same in the lowered position, substantially as described. 70

2. A mobile mount and emplacement for heavy artillery, comprising a base ring, a gun platform supported thereon, and a gun carriage and gun mounted on said platform, trucks supporting the ends of said platform, means for raising said base ring and the parts supported thereon clear of said trucks, and a mobile auxiliary platform comprising a main frame and wing plates hinged thereto, with means for raising and lowering said wing plates and securing the same in the lowered position, trucks supporting the ends of said main frame, and means for lowering said main frame to the ground while still supported on said trucks, 85 substantially as described.

3. A mobile mount and emplacement for heavy artillery, comprising a base ring, a gun platform supported thereon, and a gun carriage and gun mounted on said platform, trucks supporting the ends of said platform, means for raising said base ring and the parts supported thereon clear of said trucks, and a mobile auxiliary platform comprising a main frame and wing plates hinged thereto, with means for raising and lowering said wing plates and securing the same in the lowered position, means for moving said base ring and the parts carried thereby on to said main frame, and means for securing 100 said base ring to said main frame, substantially as described.

4. A mobile mount and emplacement for heavy artillery, comprising a base ring, a gun platform supported thereon, and a gun carriage and gun mounted on said platform, trucks supporting the ends of said platform, means for raising said base ring and the parts supported thereon clear of said trucks, and a mobile auxiliary platform comprising a main frame and wing plates hinged thereto, with means for raising and lowering said wing plates and securing the same in the lowered position, trucks supporting the ends of said main frame, and means for lowering said main frame to the ground while still supported on said trucks, means for moving said base ring and the parts carried thereby on to said main frame, and means for securing said base ring to said main frame, substantially as described. 115

5. A mobile mount and emplacement for heavy artillery, comprising a base ring, a gun platform supported thereon, and a gun carriage and gun mounted on said platform, 130

trucks supporting the ends of said platform, jacks carried by said base ring for raising said base ring and the parts supported thereon clear of said trucks, and a mobile auxiliary platform comprising a main frame and wing plates hinged thereto, with means for raising and lowering said wing plates and securing the same in the lowered position, means for moving said base ring and the parts carried thereby on to said main frame, and means for securing said base ring to said main frame, substantially as described.

6. A mobile mount and emplacement for heavy artillery, comprising a base ring, a gun platform supported thereon, and a gun carriage and gun mounted on said platform, trucks supporting the ends of said platform, jacks carried by said base ring for raising said base ring and the parts supported thereon clear of said trucks, and a mobile auxiliary platform comprising a main frame and wing plates hinged thereto, with means for raising and lowering said wing plates and securing the same in the lowered position, trucks supporting the ends of said main frame, means for lowering said main frame to the ground while still supported on said trucks, means for moving said base ring and the parts carried thereby on to said main frame, and means for securing said base ring to said main frame, substantially as described.

7. A mobile mount and emplacement for heavy artillery, comprising a base ring, a gun platform supported thereon, and a gun carriage and gun mounted on said platform, and a mobile auxiliary platform comprising a main frame and wing plates hinged thereto, with means for raising and lowering said wing plates and securing the same in the lowered position, trucks supporting the ends of said main frame, means for lowering said main frame to the ground while still supported on said trucks, means for moving said base ring and the parts carried thereby on to said main frame, and means for securing said base ring to said main frame, substantially as described.

8. A mobile mount and emplacement for heavy artillery, comprising a base ring, a gun platform supported thereon, and a gun carriage and gun mounted on said platform, and a mobile auxiliary platform comprising a main frame and wing plates hinged thereto, with means for raising and lowering said wing plates and securing the same in the lowered position, locking arms hinged to said main frame and adapted to be swung over said wing plates when said plates are in the lowered position, means for moving said base ring and the parts carried thereby on to said main frame, and means for securing said base ring to said main frame, substantially as described.

65 9. A mobile mount and emplacement for

heavy artillery, comprising a base ring, a gun platform supported thereon, and a gun carriage and gun mounted on said platform, and a mobile auxiliary platform comprising a main frame and wing plates hinged thereto, with means for raising and lowering said plates and securing the same in the lowered position, trucks supporting the ends of said main frame, means for lowering said main frame to the ground while still supported on said trucks, locking arms hinged to said main frame and adapted to be swung over said wing plates when said plates are in the lowered position, means for moving said base ring and the parts carried thereby on to said main frame, and means for securing said base ring to said main frame, substantially as described.

10. A mobile mount and emplacement for heavy artillery, comprising a base ring, a gun platform supported thereon, and a gun carriage and gun mounted on said platform, trucks supporting the ends of said platform, jacks secured to said base ring for raising said base ring and the parts supported thereon clear of said trucks, a mobile auxiliary platform, means for moving said base ring and the parts carried thereby on to said auxiliary platform, and means for securing said base ring to said auxiliary platform, substantially as described.

11. An auxiliary movable platform for use in emplacements for heavy artillery, comprising a main frame, wing plates hinged thereto, means for raising and lowering said wing plates, with locking arms hinged to said main frame and adapted to be swung over and secured to said wing plates, for locking said wing plates in the lowered position, substantially as described.

105 12. An auxiliary movable platform for use in emplacements for heavy artillery, comprising a main frame, wing plates hinged thereto, means for raising and lowering said wing plates, with locking arms hinged to said main frame and adapted to be swung over and secured to said wing plates, for locking said wing plates in the lowered position, said wing plates being provided with spades projecting from the ground side thereof when in the lowered position, substantially as described.

110 13. An auxiliary movable platform for use in emplacements for heavy artillery, comprising a main frame, wing plates hinged thereto provided with perforations adapted to receive driven stakes, means for raising and lowering said wing plates, with locking arms hinged to said main frame and adapted to be swung over and secured to said wing plates, for locking said wing plates in the lowered position, substantially as described.

115 14. An auxiliary movable platform for use in emplacements for heavy artillery,

105

110

115

120

125

130

comprising a main frame, wing plates hinged thereto provided with perforations adapted to receive driven stakes, means for raising and lowering said wing plates, with locking 5 arms hinged to said main frame and adapted to be swung over and secured to said wing plates, for locking said wing plates in the lowered position, said wing plates being provided with spades projecting from the 10 ground side thereof when in the lowered position, substantially as described.

15. An auxiliary movable platform for use in emplacements for heavy artillery, comprising a main frame, jacks for raising and lowering same between the traveling and firing positions, wing plates hinged to said main frame provided with perforations adapted to receive driven stakes, means for raising and lowering said wing plates, with 20 locking arms hinged to said main frame and adapted to be swung over and secured to said wing plates in the lowered position, substantially as described.

25. An auxiliary movable platform for use in emplacements for heavy artillery,

comprising a main frame, a racer and traversing system mounted thereon, jacks for lowering and raising said main frame between the traveling and firing positions, wing plates hinged to said main frame, 30 means for raising and lowering said wing plates, with locking arms hinged to said main frame and adapted to be swung over and secured to said wing plates in the lowered position, substantially as described. 35

17. A mobile mount and emplacement for artillery comprising a main frame, a racer and traversing system mounted thereon, a gun and carriage mounted on said racer, jacks for lowering and raising said main 40 frame between the traveling and firing positions, wing plates hinged to said main frame, means for raising and lowering said wing plates, with locking arms hinged to said main frame and adapted to be swung over 45 and secured to said wing plates in the lowered position, substantially as described.

In testimony whereof, I affix my signature.

MEADE WILDRICK.
